UNITED STATES PATENT OFFICE

130,473

DESIGN FOR A SCOUT BOMBER AIRPLANE

Edward H. Heinemann, Los Angeles, Calif., assignor to Douglas Aircraft Company, Inc., Santa Monica, Calif.

Application August 2, 1940, Serial No. 94,129

Term of patent 7 years

To all whom it may concern:

Be it known that I, Edward H. Heinemann, a citizen of the United States and a resident of Los Angeles, in the county of Los Angeles and State of California, have invented a new, original, and ornamental Design for a Scout Bomber Airplane, of which the following is a specification, reference being had in the accompanying drawings, forming part thereof.

Figure 1 is a plan view of the subject airplane;

Figure 2 is a front elevational view of the airplane depicted by Figure 1;

Figure 3 is a side elevational view of the airplane depicted by Figure 2.

Figure 4 is a bottom plan view of the airplane depicted by Figure 3.

I claim:

The ornamental design for a scout bomber airplane, substantially as shown.

EDWARD H. HEINEMANN.
